END CLOSURE FOR A CONTAINER

Leo M. Harvey, Los Angeles, and Ralph W. Hilton, Palos Verdes Estates, Calif., assignors to Harvey Aluminum (Incorporated), Torrance, Calif., a corporation of California

Filed Mar. 17, 1965, Ser. No. 84,312

Term of patent 14 years

(Cl. D58—26)

FIG. 1.

FIG. 2.

FIG. 3.

FIG. 1 is a top perspective view of an end closure for a container, embodying our new design;

FIG. 2 is another top perspective view; and

FIG. 3 is a top plan view thereof on an enlarged scale.

We claim:

The ornamental design for an end closure for a container, as shown.
